DESIGN FOR A PHONOGRAPH CABINET OR THE LIKE

Henry T. Roberts, Chicago, Ill., assignor to J. P.
Seeburg Corporation, Chicago, Ill., a corporation of Illinois

Application December 5, 1938, Serial No. 81,573

Term of patent 3½ years

To all whom it may concern:

Be it known that I, Henry T. Roberts, a citizen of the United States and a resident of Chicago, in the county of Cook and State of Illinois, have invented a new, original, and ornamental Design for a Phonograph Cabinet or the like, of which the following is a specification, reference being had to the accompanying drawings, forming a part thereof.

Figure 1 is a front perspective view of a phonograph cabinet or the like showing my new design;

Figure 2 is a top plan view thereof, and

Figure 3 is a side elevation thereof.

I claim:

The ornamental design for a phonograph cabinet or the like, substantially as shown.

HENRY T. ROBERTS.
